UNITED STATES PATENT OFFICE.

JOHN D. McEWEN, OF PITTSBURGH, PENNSYLVANIA, ASSIGNOR TO LEE C. MOORE & COMPANY, INCORPORATED, OF PITTSBURGH, PENNSYLVANIA, A CORPORATION OF PENNSYLVANIA.

DERRICK.

Application filed April 19, 1926. Serial No. 102,899.

The invention relates to structural steel derricks for oil, gas and other wells, and for other purposes, and which include corner columns and struts and cross-bracing connected to the columns to form panels.

When, for example, such derricks are used for drilling or pumping oil or gas wells, they must be stronger for effecting some operations than for effecting others. Specifically, materially greater derrick strength is required for drilling a well than for pumping it. Also, materially greater strength is required for pulling a well casing than for pumping the well. Hence, after a well has been drilled, the derrick, assuming that it remains unchanged, is much stronger than is required for pumping the well, which means that a substantial part of the derrick structure is idle and useless during the pumping period and until it may be desirable to pull the casing.

An object of this invention is to provide a structural steel derrick having its corner columns formed of angle bars which are provided with simple and effective means for attaching reenforcing members to the columns in such a way that the members, when not required for strengthening the derrick columns, may be readily removed and used on other derricks, and that the same or similar reenforcing members may be again attached to the columns.

Another object of this invention is to provide a structural steel derrick having its corner columns reenforced in such manner that the derrick columns and reenforcing members constitute a composite column having a large radius of gyration and accordingly increased strength for a given cross-sectional area of metal in the main and reenforcing column members.

The invention is illustrated in the accompanying drawings, of which Fig. 1 is an elevation of a derrick embodying the invention; Fig. 2 an elevation to enlarged scale of a portion of a column of the derrick of Fig. 1; Fig. 3 a transverse sectional view taken on the line III—III, Fig. 2, showing a reenforcing member attached to the col-

umn; and Fig. 4 a view corresponding to Fig. 3 showing the column when its reenforcing member is attached from it.

According to this invention each corner column of a structural steel derrick is formed of angle bars positioned with their backs facing outwardly of the derrick and their legs parallel to the sides of the derrick, and provision is made for removably attaching to each corner column a reenforcing angle arranged with its back facing inwardly of the derrick. For this purpose bracket angle bars are preferably attached at intervals to the backs of the column-forming angle bars, the outstanding legs of the bracket angle bars being perforated for removably attaching the column-reenforcing angle bars to them for strengthening the derrick for heavy duty. While the bracket angles may be attached to the columns at various positions, they are preferably attached at the panel points of the columns, and they are preferably arranged in pairs at such points. Additional bracket angles may be provided between the panel points.

Referring now to the illustrative embodiment of the invention, Fig. 1 shows a derrick comprising corner columns 1 which are connected to each other by cross-bracing 2 and struts 3, the cross-bracing and struts forming panels in the customary manner, the panel points being indicated at 4. Each column 1 comprises an angle or a series of angles positioned with their backs facing outwardly of the derrick and their sides parallel to those of the derricks. At each panel point a pair of bracket angles 5 is attached to the back of column 1, the outstanding legs of the bracket angles forming a right-angle pocket for the reception of an angle bar 6 for reenforcing the column. The bracket angles are provided with perforations 16 (Fig. 4) for receiving bolts 7 for the attachment of column-reenforcing angles 6, and the latter are preferably provided with slots to receive the bolts, slots being used rather than round holes to compensate for inaccuracies in the spacing and positions of perforations 16 in the bracket angles. In

Fig. 1 the right hand column is shown as having a reenforcing angle bar 6, and the left column with the reenforcing angle bar removed.

5 To simplify the construction and erection of the derrick, the ends of cross-bracing 2 and of struts 3 are preferably connected to the columns by bolts 8 which are also used for attaching bracket angles 5 to the 10 columns. At the splice points of the angle bars, one of which is indicated at 10, a splice angle or bent plate 11 may be attached to the inner faces of these angle bars, as shown in Fig. 3, these splice angle bars being arranged between the column angle bars and the ends of the struts and cross-bracing.

For further connecting reenforcing column angle bars 6 to the permanent column members 1, shorter bracket angle bars 12 20 may be attached to columns 1 between the panel points in a manner similar to the attachment of bracket angle bars 6, and as is clearly shown in Fig. 2.

The arrangement of the derrick corner 25 columns 1, the bracket angles 5, and the reenforcing angle bars 6 to constitute an expanded section as shown in Figs. 3 and 4, is a decided advantage over the derrick reenforcing structures heretofore proposed, it 30 being obvious that such a disposition of the cooperating parts substantially increases the strength of the reinforced columns.

When a derrick embodying this invention is erected for drilling a well, reenforcing 35 angle bars 6 are customarily attached to the bracket angles 5 of each corner column 1. After the well has been drilled, and the correspondingly heavy duty of the derrick terminated (unless it becomes desirable later 40 to pull the casing), the reenforcing angle bars 6 are removed from the columns, leaving bracket angle bars 5 in place. The reenforcing angle bars may then be used on another derrick, and either they, or similar 45 reenforcing angle bars, may be later attached to the brackets should it become necessary or desirable to call upon the derrick to perform further heavy duty.

According to the provisions of the patent 50 statutes, I have explained the principle and operation of my invention and have illustrated and described what I now consider to represent its best embodiment. However, I desire to have it understood that, within the 55 scope of the appended claims, the invention may be practiced by other forms of construction than that particularly illustrated and described.

I claim as my invention:

60 1. A derrick having corner columns and struts and cross-bracing connected to the columns to form panels, each column comprising an angle bar positioned with its back facing outwardly of and its legs parallel to the sides of the derrick, and bracket

angle bars attached to the backs of said column-forming angle bars at the panel points, the outstanding legs of said bracket angle bars being perforated for removably attaching to them column-reenforcing angle 70 bars to strengthen the derrick for heavy duty.

2. A derrick having corner columns and struts and cross-bracing connected to the columns to form panels, each column comprising an angle bar positioned with its back facing outwardly of and its legs parallel to the sides of the derrick, and bracket angle bars attached in pairs to the backs of said column-forming angle bars and at the 75 panel points of the column, the outstanding legs of said bracket angle bars forming right-angled pockets for receiving, and being perforated for removably attaching to them column-reenforcing angle bars to strengthen, 80 85 the derrick for heavy duty.

3. A derrick having corner columns and struts and cross-bracing, each column comprising an angle bar positioned with its back facing outwardly of and its legs parallel to the sides of the derrick, bracket angle bars arranged in pairs on the backs of said column-forming angle bars, and a single set of clamping members for attaching 90 said bracket angle bars and the ends of 95 said struts and cross-bracing to said column-forming angle bars, the outstanding legs of said bracket angle bars forming right angled pockets for receiving, and being perforated for removably attaching to them 100 reenforcing angle bars to strengthen the derrick for heavy duty.

4. A derrick having corner columns and struts and cross-bracing connected to the columns to form panels, each column comprising an angle bar positioned with its back facing outwardly of and its legs parallel to the sides of the derrick, bracket angle bars attached at the panel points to the 105 back of said column-forming angle bars and having their outstanding legs provided with 110 perforations, and column-reenforcing angle bars bolted to the outstanding legs of said bracket angle bars for strengthening the derrick for heavy duty.

115 5. A derrick having corner columns and struts and cross-bracing connected to the columns to form panels, each column comprising an angle bar positioned with its back facing outwardly of and its legs parallel to the sides of the derrick, bracket angle bars attached in pairs to the backs of said column-forming angle bars and at the panel 120 points of the column, said bracket angles having their outstanding legs provided with 125 perforations, and column-reenforcing angle bars bolted to the outstanding legs of said bracket angle bars for strengthening the derrick for heavy duty.

130 6. In a derrick structure having corner

columns made up of two parallel series of angle bar sections placed end to end in the respective series, the bars of one series being back to back relative to those of the other series, the joints between adjacent sections of one series being staggered with respect to the adjacent joint of the other series,

the combination of angle bar brackets adapted to connect the ends of adjacent sections of each series and to connect the two series to each other at each joint of each series.

In testimony whereof, I sign my name.
JOHN D. McEWEN.
